UNITED STATES PATENT OFFICE

ELEANOR DONALDSON, OF MINNEAPOLIS, MINNESOTA

HOSE SUPPORTER FOR WOMEN

Application filed February 24, 1931. Serial No. 517,795.

My invention relates to hose supporters for women of the type wherein an upper form-fitting garment such as a vest or step-in furnishes an upper support, and the hose supporters proper extend from the bottom of said vest to the top of the hose. It is an object of my invention to provide such a hose-supporting garment with connections between the garment and the hose such that they will readily adapt themselves by variations in length to the position of the wearer and of the wearer's limbs whether sitting, standing, stooping or walking, and will hold the hose or stockings firmly with the full extent stretched along the limbs, the uppermargin circumferentially disposed in a single plane and the seam running straight up the back of the leg. Customarily women hold up their stockings by garters or by connections from a girdle or corset affair. Round garters will hold the hose above the knee with a fair degree of firmness and smoothness, but they are uncomfortable and can only be used at the point immediately above the knee, leaving the top four inches of the hose length to be of no value and necessarily rolled about the garter. The girdle hose supporters are cumbersome because of the extra width of elastic, heavy metal fixtures and buckles, although they can be adjusted to the wearer's height and be permanently left that way. But, with such structures the back and side elastics must be left long enough for the wearer when she sits or stoops over, which means that when she stands erect the elastic will stand in an awkward and uncomfortable way both on the back and at the side which is uncomfortable to the wearer and may show under thin gowns. Also, the excess length of the elastic permits the stocking to drop at the sides and back so that it is held tightly only on the front. When the wearer sits again the stocking is drawn up behind but not in the same line, with the result that the hose is very likely to be twisted on the leg. Further, if the supporter is set far enough to the back to hold the garment down properly and keep the stocking straight, the wearer is made uncomfortable by the heavy buckle

and fastener and the undergarment is almost certain to be cut thereby.

It is the object of my invention to do away with all difficulties encountered from the use of girdle hose supporters or other known hose-supporting garments. Instead of wide webbing I use a small elastic cord which has more elasticity than the webbing and will stand washing better than webbing. I obviate entirely the use of a buckle, and so arrange the cords that perfect provision is made for adjustment to all of the various positions of the wearer without causing discomfort in any of such positions and effective always to hold the stocking in fixed position on the leg with the seam running straight up the back.

The full objects and advantages of my invention will appear in connection with the detailed description thereof and its novel features are particularly pointed out in the claims.

In the drawing illustrating an application of my invention in one form,—

Fig. 1 is a part back view of a figure showing my garment and hose supporter in position with the figure erect. Fig. 2 is a similar view from the front of the figure. Fig. 3 shows the position of the parts when the limb is greatly bent, as in the sitting posture. Fig. 4 is a view of the bottom of the garment showing the relative position of the fastener elements. Figs. 5 and 6 are details showing the means of fastening the elastic cord in position. Fig. 7 is a front plan view of one of the fasteners employed. Fig. 8 is a sectional view of the fasteners shown in Fig. 7.

The garment 10 is of any desired construction which is supported by the straps 11 from the shoulders of the wearer. To the lower edge of said garment is sewed flat fasteners 12 and 13, fastener 12 being provided with an opening 14 in which the double cord 15 is secured by means of a loop 16. The fastener 13 is provided with a second member having a tongue-piece 17 which goes through the opening 14 of the first member and secures the loop members of the cords 15 in slidably engagement between the two bands of fabric of the fastener, all as clearly shown in Fig. 5.

Three sets of fasteners 18, 19 and 20 are provided for each stocking, those numbered 18 being in front disposed at each side of the center line of the garment, and the pairs of loops 19, 20 overlapping to form relatively widely separated points of support from the lower edge 21 of the garment. It will thus be seen that the stocking is held at three points of support at its back and front and that there are six points of support from the edge of the garment and six double strands of cord extending from these points of support to the fasteners.

These double cords 15, as clearly shown in Figs. 7 and 8, have mounted thereon a distinctive type of fastener adapted to slide freely on the cord and at the same time contact substantially with the fabric and thus be subject to but little wear. As illustrated, the fastener stud 22 of usual construction is slipped on a tape 23 which is carried over the base of the hasp 24 as indicated at 25 and sewed down at the point 26. An extension of the tape 23 is also carried around the hasp and sewed down at 28, leaving a loop 29 through which the cords 15 extend, as clearly shown in Fig. 8. By this construction the fastener member proper is secured slidably on the loops of elastic cord 15 at 29, where said cords contact only with fabric and hence slide freely and are not subject to wear. This arrangement I have found to be in a high degree satisfactory, giving a long life to the elastic cord. The double loops are self-adjusting for the reason that they are fast at the point 16 of the fasteners 12 but are free to slide in the fasteners 13. Also, the stocking fasteners are at all times free to slide on the loops of elastic 15. The result of this, and of the overlapping points of support of the rear fasteners, is that when a sitting position is taken, or the limbs are sharply bent, as shown in Fig. 3, the front portions 30 of the double loops 19 and 20 will grow shorter, while the rear portions 31 will correspondingly lengthen, thus adjusting the relative lengths and maintaining a firm hold of the stocking at the back even in the most contorted positions.

The advantages of this construction have been quite fully pointed out in the description heretofore given. It insures a firm and certain holding of the upper edge of the stocking in all positions of the legs of the wearer and secures the highest degree of comfort. Also, it not only presents no protruding forms to be uncomfortable but none to be injurious to garments worn by the wearer no matter how thin and delicate the fabric may be. It is also to be noted that the hose-supporter garment to which the supporters proper are fastened, whether it be a vest, a step-in, a corselette or some form of girdle, normally has a tendency to slip up on the form of the wearer. It is a feature of my invention, therefore, not only to hold the hose or stockings

up in firm position, but also, from reverse action, to hold the lower edge of the supporting garment down. This is accomplished with a high degree of certainty and great efficiency by reason of the fact that there are twelve points of attachment to the lower edge of the garment, operating with a symmetrical pull from six points of attachment on the two stockings. This results in a constant downward pull on the entire circumferential extent of the lower edge of the garment, which keeps the garment down in its proper position, and entirely obviates the unpleasant necessity in other types of garments of the wearer pulling the garment down with her hands, which is a matter of long experience and observation.

When the leg of the wearer of the device is bent into the position shown in Fig. 3, it is apparent that except for the front stocking fastener, the pull of the elastic on one side of its associated fastener is greater than it is on the other side thereof. Therefore it is important that the parts of each loop and its associated fastener should lie in a common plane as shown. Otherwise, the fastener will be pulled out of proper position and the elastic will be crowded into an end portion of the fastener where it will not slide easily, and where it is subjected to greater wear. Furthermore, when the fastener is thus pulled out of proper position, it is apt to dig into the wearer's flesh and cause great discomfort.

I claim:

1. A hose supporter comprising a garment adapted to be supported upon the form of the wearer, a plurality of loops of double elastic cord each secured fixedly at one end and slideable at the other end in spaced relation to the lower edge of said garment, and a stocking fastener on and embracing each of said loops and freely slidable thereon.

2. A hose supporter comprising a garment adapted to be supported upon the form of the wearer, a plurality of loops of elastic cord secured at their upper ends in spaced relation to the lower edge of said garment, one point of support of some of said loops being between points of support of other of said loops, and a stocking fastener on and embracing each of said loops and freely slidable thereon.

3. A hose supporter comprising a garment adapted to be supported upon the form of the wearer, a front loop and two rear loops of elastic cord secured at their upper ends in spaced relation to the lower edge of said garment, each of said rear loops having one point of support between the points of support of the other rear loop, and a stocking fastener on and embracing each of said loops and freely slidable thereon.

4. A hose supporter comprising a garment adapted to be supported upon the form of the wearer, a plurality of separate loops of

elastic cord for each stocking secured at their upper ends in spaced relation to the lower edge of said garment, one point of support of one of said loops lying between points of support of another of said loops, and a stocking fastener on and embracing each of said loops and freely slideable thereon, one of said fasteners being adapted to secure the front of the stocking and another fastener being adapted to secure the rear of the stocking, the parts of each loop and its associated fastener lying in a common plane.
